UNITED STATES PATENT OFFICE.

CORNELIUS B. CORCORAN, DECEASED, LATE OF NEW YORK, N. Y.; BY MICHAEL J. CORCORAN, ADMINISTRATOR, OF BROOKLYN, AND ALFRED G. F. KUROWSKI, OF BROOKLYN, NEW YORK, ASSIGNEES TO UNDERWOOD TYPEWRITER COMPANY, OF NEW YORK, N. Y., A CORPORATION OF DELAWARE.

TYPEWRITING MACHINE.

Original application filed December 30, 1922, Serial No. 609,793. Divided and this application filed January 21, 1926. Serial No. 82,647.

This invention relates to means for facilitating the releasing and returning of a typewriter-carriage in a sound-deadening casing with the carriage-release lever and carriage-return arm readily operable from the exterior of the casing.

In an Underwood portable typewriting machine the carriage is mounted considerably to the rear of the machine, so that when the machine is placed in a sound-deadening casing the carriage is much nearer the top than the front of the casing.

A feature of the present invention relates to the provision of a carriage-release lever protruding through a slot in the top of the casing. The carriage-release lever is pivotally mounted on a fixed supporting bracket which extends upwardly and serves as a carriage-return handle. Both the lever and the bracket can be easily attached to or detached from the machine, so that a standard machine may be used with or without the casing with little or no alteration thereto.

Another feature of the present invention relates to the provision of means between the carriage-return arm and the carriage-release lever for limiting and steadyng the throw of the latter. Said means may comprise an outwardly-extending prong on the carriage-return arm having shoulders for engagement with a pin on the carriage-release lever for limiting the throw of the lever, the pin being provided with a head for engagement with the rear face of the prong for steadyng the lever against forward or rearward movement.

This application is a division of application, Serial No. 609,793, filed December 30, 1922.

Other features and advantages will hereinafter appear.

In the accompanying drawings,

Figure 1 is an end view of a sound-deadening casing with a typewriting machine therein, partly in cross-section, for illustrating the invention more clearly.

Figure 2 is a front view of the right-hand end of the carriage, showing the carriage-release mechanism and the carriage-return arm.

The casing comprises a body portion 10

divided longitudinally by a plate 11, which extends from one to the other of the side walls 12 of the casing. The plate 11 is offset at its lower edge to form a flange 13, through which are passed wood screws 14, securing the plate to the base 15 of the body-part of the casing. The plate 11 may be further braced by means of a strip 16 extending longitudinally thereof on the base 15. A similar strip 17 may be extended from side to side of the body-part, at the forward edge thereof, where the cover engages the base. The plate 11, together with the rear wall 18 of the part 10, and the side walls of the latter, forms an interior chamber adapted to receive the main frame 19 and the carriage 20 of a typewriting machine. The keyboard-extension 21 of the machine protrudes through, and forward of, the plate 11, so that the keyboard may be accessible when the outer cover (not shown) is removed. This interior chamber has the rear wall thereof lined with sound-deadening material 22; the side walls thereof with sound-deadening material 23; the base thereof with sound-deadening material 24; and the front thereof with sound-deadening material 25, which latter is suitably secured to the plate 11. This interior chamber is also provided with a cover 26, adapted to be swung up from its normal position, in which position access may be had to the machine, for erasures and the like. For centering and holding the machine to the casing base 15, the rear feet 27 of the machine are moved into brackets 28 and the front feet 29 into disks 30. The front of the machine is locked against upward movement by a plate 31, secured to the upper edge of the plate 11, and which crosses over, and fits down upon, the front plate 32 of the machine. This plate 31 is provided with a sound-deadening lining 33 and forms an upward continuation of the front wall of the interior chamber to the lower front edge of the interior cover 26 when the latter is in normal position.

The cover, like the rest of the interior casing, is provided with a lining 34; and this lining is provided with a facing-piece 35, of sheet-metal or other material, to prevent fouling of the paper, in the machine,

on the lining 34 as the carriage is moved in letter-feed and return directions. The lower edges of the side lining-members 36 of the cover are held by strips 37. In the 5 front of the cover is a window, through which the writing on the platen may be observed. A window-pane 38, of glass or other transparent material, is set into a frame provided therefor in the cover.

10 Since the machine is to be operated in the sound-proof inner casing, and since the side walls 12 of the casing-part 10 form also the side walls of the interior sound-proof chamber, the length of the several parts of the 15 casing must be such as to allow for full movement of the carriage in letter-feed and return directions on the machine. Secured to the carriage, however, are various operating levers and arms which should be accessible from the outside of the sound-proof chamber. These levers and arms comprise a line-space lever (not shown), a carriage-rack-release-lever 39 and a carriage-return arm 40. If these levers and arms are to 20 project to the outside of the sound-proof chamber, the latter must be slotted to permit them to travel therewith along with the carriage. Such a slot is shown at 41 in the cover at the rear of the window-pane. 25 30 Resilient cushions 42 are provided which come together to close the slot, except at the points where the levers and arms protrude therethrough.

The carriage-return arm 40 is a fixed arm 35 at the front, and at the right-hand end of the platen, which forms a continuation of a bracket 43, which is extended under the platen-axle, to the rear thereof, and made fast to an ear 44 on the right-hand carriage 40 side plate 45. The carriage-rack-release-lever 39 is a bell-crank-lever pivoted at 46 to the carriage-return arm. One arm 47 of this bell-crank-lever projects rightward, and terminates in a rearwardly-offset lip 48, 45 which underlies, and is adapted to engage, a lip or detent 49, offset leftward from the rack-release-lever 50, commonly found in the Underwood standard portable typewriter. The lever 50 is a lever pivoted on the platen-50 axle, and having a rearward extension 51, carrying a finger-piece 52, by depression of which the carriage-rack has heretofore been released. The lever 50 has a yoke 53, in which is fitted the end 54 of an arm 55, forming part of a bell-crank-lever pivoted at 56 to the right-hand carriage side plate. The other arm 57 of this bell-crank-lever supports the right-hand end of the carriage-rack 58. The left-hand end of the carriage-rack 58 55 is supported by an arm (not shown), but similar to the arm 57 pivoted at the right-hand side of the carriage. In the normal position of the parts the rack 58 meshes with a drive-pinion 59. The escapement mechanism and spring-drum by means of

which the rack 58 is driven from the pinion 59, are not shown, but may be such as are found in the Underwood machine. When the bell-crank-lever 55—57 is rocked counterclockwise, by the lever 50, the rack is 70 lifted out of engagement with the pinion 59, to permit the free movement of the carriage. As just described, leftward throw of the rack-release-lever 39 moves the lever 50 in such manner as to release the rack. 75

The carriage-return arm 40 has a rightward projecting prong or extension 60, the upper surface 61 of which is shaped on an arc struck from the pivot 46 as a center; and the lever 39 carries a pin 62 adapted to ride on the edge 61, and, by abutment with shoulders 63 and 64, respectively, at the left and right hand ends of the curve 61, to determine the throw of the lever 39 in either direction. Throw of the lever 39 to the left first releases the rack; and continued leftward pressure on the lever 39, after the pin 62 has struck the shoulder 63, will result in leftward movement of the carriage. To steady the lever 39 against forward and 90 rearward movement on its pivot 46, the pin 62 is provided with a head 65 for engagement with the rear face of the prong 60 on the carriage-return arm. 95

Variations may be resorted to within the scope of the invention, and portions of the improvements may be used without others.

Having thus described the invention, we claim:

1. In a typewriting machine, a platen, a platen-carriage, a rack on the carriage, a pinion for engagement with the rack to effect letter-feed movement of the carriage, a lever on the carriage for disengaging the rack from the pinion when rocked in a plane at right angles to the rack, a shoulder on the lever, and a second lever pivoted to swing at right angles to the plane of movement of the first lever and to project through an opening in a sound-proof casing for the machine; the second lever being a bell-crank lever, one arm of which is adapted to engage the offset on the first lever and to rock the latter to release the rack when the second lever is swung on its pivot. 100

2. In a typewriting machine, a platen, a platen-carriage, a rack on the carriage, a pinion for engagement with the rack to effect letter-feed movement of the carriage, a lever on the carriage for disengaging the rack from the pinion when rocked in a plane at right angles to the rack, a shoulder on the lever, a second lever pivoted to swing at right angles to the plane of movement of the first lever and to project through an opening in a sound-proof casing for the machine; the second lever being a bell-crank lever, one arm of which is adapted to engage the offset on the first lever and to rock the latter to release the rack when the sec- 105 110 115 120 125 130

ond lever is swung on its pivot, and a bracket on the platen-carriage to which the second lever is pivoted; the bracket having as an extension thereof a carriage-return arm adapted to project through the opening in the sound-proof casing.

3. In a typewriting machine, a platen, a platen-carriage, a rack on the carriage, a pinion for engagement with the rack to effect letter-feed movement of the carriage, a lever on the carriage for disengaging the rack from the pinion when rocked in a plane at right angles to the rack, a shoulder on the lever, a second lever pivoted to swing at right angles to the plane of movement of the first lever and to project through an opening in a sound-proof casing for the machine; the second lever being a bell-crank lever, one arm of which is adapted to engage the offset on the first lever and to rock the latter to release the rack when the second lever is swung on its pivot, a bracket on the platen-carriage to which the second lever is pivoted; the second lever having a pin or shoulder thereon adapted to ride on a portion of the bracket, and shoulders on the bracket for determining the throw of such lever.

4. In a typewriting machine, a platen, a platen-carriage, a rack on the carriage, a pinion for engagement with the rack to effect letter-feed movement of the carriage, a lever on the carriage for disengaging the rack from the pinion when rocked in a plane at right angles to the rack, a shoulder on the lever, a second lever pivoted to swing at right angles to the plane of movement of the first lever and to project through an opening in a sound-proof casing for the machine; the second lever being a bell-crank lever, one arm of which is adapted to engage the offset on the first lever and to rock the latter to release the rack when the second lever is swung on its pivot, and a bracket on the platen-carriage to which the second lever is pivoted; the second lever having a headed pin thereon adapted to ride on a portion of the bracket, with such portion of the bracket between the lever and the head of the pin, to steady the lever against forward and rearward displacement.

5. In a typewriting machine, a platen, a platen-carriage, a rack on the carriage, a pinion for engagement with the rack to effect letter-feed movement of the carriage, a lever on the carriage for disengaging the rack from the pinion when rocked in a plane at right angles to the rack, a shoulder

on the lever, a second lever pivoted to swing at right angles to the plane of movement of the first lever and to project through an opening in a sound-proof casing for the machine, and a carriage-return arm fast to the carriage and adapted to project through the opening in the sound-proof casing; the second lever being pivoted to the carriage-return arm.

6. In a typewriting machine, a platen, a platen-carriage, a rack on the carriage, a pinion for engagement with the rack to effect letter-feed movement of the carriage, a lever on the carriage for disengaging the rack from the pinion when rocked in a plane at right angles to the rack, a shoulder on the lever, a second lever pivoted to swing at right angles to the plane of movement of the first lever and to project through an opening in a sound-proof casing for the machine, a carriage-return arm fast to the carriage and adapted to project through the opening in the sound-proof casing; the second lever being pivoted to the carriage-return arm, a lateral extension or prong on the carriage-return arm having shoulders thereon, and a pin or shoulder on the second lever adapted to engage the shoulders on the carriage-return arm to determine the throw of the second lever.

7. In a typewriting machine, a platen, a platen-carriage, a rack on the carriage, a pinion for engagement with the rack to effect letter-feed movement of the carriage, a lever on the carriage for disengaging the rack from the pinion when rocked in a plane at right angles to the rack, a shoulder on the lever, a second lever pivoted to swing at right angles to the plane of movement of the first lever and to project through an opening in a sound-proof casing for the machine, a carriage-return arm fast to the carriage and adapted to project through the opening in the sound-deadening casing; the second lever being pivoted to the carriage-return arm, a lateral extension or prong on the carriage-return arm having shoulders thereon, and a headed pin on the second lever between the head of which and the lever the extension or prong lies to steady the second lever against forward and rearward displacement.

MICHAEL J. CORCORAN,
*Administrator of the estate of Cornelius B.
Corcoran, deceased.*

ALFRED G. F. KUROWSKI.
